UNITED STATES PATENT OFFICE.

ADOLPH EICHLER, OF DIXON, ILLINOIS, ASSIGNOR TO HIMSELF, JOHN HOFFMAN, AND MAX EICHLER, OF DIXON, ILLINOIS.

ASH-RECEPACLE.

No. 909,070.

Specification of Letters Patent.

Patented Jan. 5, 1909.

Application filed January 31, 1908. Serial No. 413,596.

To all whom it may concern:

Be it known that I, ADOLPH EICHLER, a citizen of the United States, residing at Dixon, Lee county, Illinois, have invented 5 certain new and useful Improvements in Ash-Receptacles; and I do hereby declare the following to be a full, clear, and exact description of the invention, such as will enable others skilled in the art to which it appertains 10 to make and use the same.

This invention relates to certain improvements in ash receptacles, and the like; and the objects and nature of the invention will be readily understood by those skilled in the 15 art in the light of the following explanation of the accompanying drawings illustrating what I now consider my preferred embodiment from among other arrangements within the spirit and scope of my invention.

20 An object of the invention is to provide comparatively simple, efficient, durable and improved means, whereby ashes, and the like, can be dumped or otherwise discharged into a can or other receptacle without permitting objectionable escape of dust at the 25 exterior of the receptacle and the cover or housing therefor.

The invention consists in certain novel features in construction and arrangements 30 and combinations of parts as more fully and particularly explained and set forth herein-after.

Referring to the accompanying drawings:—Figure 1, is a front elevation of the 35 receptacle showing the door or slide in opened position against the tension of its springs and as though depressed by the foot. Fig. 2, is a vertical longitudinal section, extending through said slide and showing the 40 same in normal closed position. Fig. 3, is a horizontal section taken in the plane of the line 3—3, Fig. 1. Fig. 4, is a detail elevation of the ash can.

In the specific example illustrated in the 45 accompanying drawings, I show a cylindrical ash can 1, having an open top, and suitable fixed exterior side handles or hand holds 2, usually arranged a distance below the top edge of the can and diametrically opposite each other. I show this can at its upper and lower ends, formed with exterior 50 annular projecting beads, seams or enlargements 3, whereby the can is braced and stiffened.

The can 1, is inclosed within and forms 55 the floor or bottom of a housing, casing or inclosure 4, formed by a cylindrical body having an open bottom or lower end, and closed at the upper end by a usually conical top or cap 5, around its annular lower edge 60 fixedly secured to the annular upper edge of the cylindrical body by an annular seam or joint forming an annular exterior outwardly projecting or horizontal flange 6. The cylindrical body is in length greater than the 65 length of the ash can or pan, for instance, in the example illustrated the cylindrical body is about twice the length or height of the cylindrical ash can. At an intermediate point in its length, the cylindrical body is 70 formed with an internal annular downwardly and inwardly tapered flange or lip 7, fixed around its upper outer end or edge to the cylindrical body. This flange is located 75 and arranged to cover the top edge of the ash can and project down into the can, and is so formed as to receive the upper edge of the can in the upwardly reducing annular space between the inner or under surface of the flange and the inner surface of the cy- 80 lindrical body. At its lower end, the cylindrical body can, if so desired, be formed with an exterior strengthening bead 8. The cylindrical body is formed to slip down on the exterior of the ash can in sliding engagement with the exterior beads 3, thereof with the lower end of the body passing down snugly around the lower bead 3, and into engagement with the floor or ground, thereby forcing the upper end of the can snugly into 90 the tapering recess under the internal flange 7.

Access to the interior of the casing, at a point above the open top of the can, is gained through a side opening 9, in the cylindrical 95 body which opening is arranged above flange 7, and below the conical top of the casing. The lower end of this opening usually terminates at the upper end of said flange 7. Suitable means are provided to maintain said 100 opening normally closed, and yet so as to permit quick and easy uncovering thereof when desired to discharge ashes or other material into the can. For instance, I show a vertically movable slide or door 10, for this 105 purpose, and arranged on the exterior of the cylindrical body with its end edges arranged under the exterior vertical guide strips 11,

secured on the cylindrical body. The upward movement of said door is limited by the exterior cross strip 12, under which the top edge of the door engages when said door is in 5 its normal closed position. The door is yieldingly upheld against stop strip 12, and in closed position, by one or more springs. For instance, I show two retractive coiled 10 springs 13, at their upper ends secured to the projecting flange 6, and at their lower ends secured to the lower portions of the opposite ends of the door.

Suitable means are provided whereby the door can be depressed to uncover the opening 15 and thus held in opened position while the ashes are being emptied or discharged through the opening. For instance, I show the door, at the center of its lower portion formed with a rigid outwardly projecting 20 foot piece or handle 14, on which the operator can place his foot and conveniently depress and open the door. On the removal of the foot, the door under the impulse of the springs, will quickly return to closed position, or if when the door has been opened a 25 coal hod is inserted through the opening, the hod will hold the door open, and the springs will quickly close the door on the removal of the hod.

30 The casing or housing can be composed of any suitable material, such as sheet metal of a suitable gage, and if so desired can be fitted on any ash can adapted to receive the same.

The casing can be readily lifted from and 35 applied to the can shown, and the casing taper flange and the exterior beads of the can form tight joints against the escape of dust around the exterior of the can, although I do not wish to limit all features of my invention 40 to the can shown.

45 The conical top of the casing tends to cause precipitation of the dust within the casing into the can, and tends to reduce escape thereof through the opening when the door is depressed, although I do not wish to limit myself to the conical formation of the casing top.

50 It is evident that various modifications might be resorted to in the forms and construction shown and hence I do not wish to limit myself to the exact disclosure hereof.

What I claim is:—

55 1. An ash receptacle, or the like, comprising a hollow elongated casing having a lower open end and adapted to internally receive an ash can, said casing having a closed upper end, and an internal annular tapered flange in combination with an open top ash can adapted to extend removably 60 into said casing and at its upper end formed to fit the under surface of said flange and form a tight joint therewith and around its lower end adapted to fit snugly within the lower end of said casing to prevent escape of 65 dust therefrom, said casing provided with a

side opening below its upper end and above said flange and provided with a closure.

2. A device of the character, substantially as set forth, comprising an elongated casing 70 open at the lower end and closed at the upper end and intermediate the ends thereof having a side opening, and provided with an internal annular downwardly and inwardly tapering flange arranged above the lower end of the casing and below said opening, 75 and a door normally closing said opening in combination with an open top ash can down on the exterior of which said casing is adapted to removably and longitudinally fit with the upper edge of said can fitting between 80 said flange and the wall of said casing to form a slip joint, the lower ends of the casing and of the can forming a slip joint, substantially as described.

3. A vertically - elongated open - bottom 85 casing having a closed top forming a dust collecting chamber and adapted to receive and slide down on the exterior of an open top ash can, said casing intermediate its ends and below said chamber formed with a side opening, and a door normally held closing 90 said opening and provided with means whereby the same can be moved to uncover said opening in combination with an ash can removably arranged within and forming a 95 slip joint with said casing and having its upper end below said opening.

4. An elongated casing having an open lower end and an upwardly tapering closed top, said casing intermediate its ends having 100 a side opening, whereby the interior chamber formed by the casing extends a distance above said opening, forming a top dust collection chamber above the open top of the ash can, a door normally closing said opening, 105 and means yieldingly holding said door in closed position in combination with an open top ash can removably fitted within said casing and having its open top below said side opening.

5. An elongated casing having an open lower end and an elevated closed top, said casing intermediate its ends having a side opening, whereby the interior chamber formed by the casing extends a distance above said opening, for the collection of dust, a door normally closing said opening, and means yieldingly holding said door in closed position in combination with an open top ash can removably and longitudinally arranged within said casing with its open top below said side opening, said can forming a slip joint with the interior surface of said casing to prevent passage of dust to the exterior thereof.

6. An ash can having exterior annular beads, a casing having an open lower end and adapted to removably and longitudinally fit down on said can and form slip joints with said beads, and having an internal intermediate annular flange to snugly fit within 130

the top edge of said can, said casing having an opening above said flange and a normally closed door therefor.

7. An open top removable ash can, in combination with a vertically elongated casing to cover and removably receive said can, said casing extending above and forming a dust collection chamber over the open top of said can and formed with an internal tapered flange fitting within the upper end of the can and forming a slip joint therewith to prevent downward passage of dust around the can, said casing below its upper end and immediately above said flange having a side opening provided with a closure.

8. An open top removable ash can, in combination with a vertically elongated cas-

ing adapted to removably and longitudinally slip down on the exterior of the can with the lower ends of the casing and can forming a 20 slip joint, the casing intermediate its length provided with an annular internal downwardly tapered flange forming a socket beneath the flange in which the upper edge of the can snugly fits, said casing provided 25 with a side opening immediately above the flange and provided with a normally closed door.

In testimony whereof I affix my signature, in presence of two witnesses.

ADOLPH EICHLER.
